UNITED STATES PATENT OFFICE.

HOWARD M. MURPHY, OF PHILADELPHIA, PENNSYLVANIA.

PIPE-CLEANER.

1,369,903.

Specification of Letters Patent.

Patented Mar. 1, 1921.

Application filed May 27, 1920. Serial No. 384,565.

To all whom it may concern:

Be it known that I, HOWARD M. MURPHY, a citizen of the United States, residing at Philadelphia, in the county of Philadelphia and State of Pennsylvania, have invented 5 certain new and useful Improvements in Pipe-Cleaners, of which the following is a specification.

This invention relates to pipe-stem-cleaners, and more specifically to a device for boring incrustations and wiping gummy accumulations out of tobacco-pipe-stems.

The main object of this invention is to generally improve upon devices of this character by providing an improved structure which is exceedingly convenient and effective, strong and durable, simple and cheap, as well as comparatively ornamental; the main parts being embodied in a shank 20 formed of a length of wire, this shank having a peripheral or helical groove that serves the several functions of clearing the cutting edge, removing the cuttings or loosened incrustations from the pipe-stem, 25 and helping to secure a wiping strip on the shank.

Other objects and advantages will be pointed out or implied in the following details of description in connection with the 30 accompanying drawings in which:

Figure 1 is a view of the device in a pipe, the pipe being in longitudinal vertical section.

Fig. 2 is an enlarged detail view of the 35 front end part of the device.

Fig. 3 is a view similar to Fig. 2, but viewed in the direction of arrow "A" of Fig. 2.

Fig. 4 is a transverse sectional view along 40 the line 4-4 of Fig. 2.

Fig. 5 is a longitudinal sectional view showing the device having a wiping strip applied thereto and in operation in a pipe-stem.

Fig. 6 is a perspective view showing the 45 manner of applying my wiping strip, or one of the wiping strips which is of special shape and will accompany my boring device as an accessory.

Referring to these drawings in detail, in 50 which similar reference characters correspond with similar parts throughout the

several views, and in which the pipe is shown merely to show the application and use of the device at a glance, the invention 55 consists in the construction and arrangement of parts which will now be described as follows:

Broadly, the device consists of a shank 1 and a head or handle 2. The shank is of 60 equal diameter throughout its length, and its front end portion is provided with a cutting edge 3, a helical or peripheral groove 4 and an approximately axially parallel slot 5. This slot, however, is not exactly parallel with the axis of rotation of the shank, but is slightly inclined to this axis and terminates thereat and in the periphery of the shank; that is, it extends through the periphery and provides a tongue 6 that is 70 parallel with the opposite side of the slot, so that a wiping strip of cloth or paper can be inserted in this slot or under this tongue by moving the strip laterally of its length, thereby avoiding the comparatively tedious 75 operation of threading the end of the strip into the slot. When the wiping strip has been thus engaged with the shank, it is to be wound helically around the shank as shown in Figs. 5 and 6, rearward of the rear 80 end of the helical groove 4, and is inserted in and withdrawn from the pipe-stem by a clockwise movement as well as a longitudinal movement, while the strip of paper is held against the handle 2 by pressure of a thumb 85 or finger of the user. The strip *s* is preferably of soft and strong tissue paper, and in practice, a package of several dozen, fifty or a hundred of these strips will be sold or given away with each of the devices for applying them. These strips may have advertising matter and directions for using printed thereon. They are preferably tapering, as shown, and the broad end may be inserted in the slot for special purposes, such, 90 for instance, as wiping out the bowls of meerschaum pipes, or in wiping out relatively large cavities in pipes of special construction. When the strip is thus wound, it is wound over the helical groove, and if 100 sufficient lateral pressure is applied to the strip, over the groove, the strip is pressed into the groove so that the latter co-acts with the slot for securing the strip on the shank.

to provide a mop-like structure in which the cutting edge may also be covered to prevent scratching the interior of a meerschaum or other very valuable pipe while wiping 5 out its bowl or other part.

The cutting edge 3 extends from the axial center to the periphery of the boring end, similar to that of an auger or twist drill, and it may properly be termed a twist drill 10 cutting edge, especially in view of the fact that it is formed at the terminal of a twist- 15 ed or helical part forming a wall of the helical groove 4.

The head or handle 2 may be of any preferred size and shape, but is preferably cylindrical and milled or knurled as shown, so that the user can rotate the device by 20 rolling the handle 2 between the thumb and finger, and can pull the device from the 25 pipe-stem without danger of the handle slipping from his grip. This form of handle is ornamental also, and may be made more so by gold-plating it to serve as an ornament to protrude from a pocket when it is in the pipe and the pipe-stem extends toward the inlet of the pocket.

It is not intended to limit this invention to the exact details of construction and arrangement as shown and described, but

changes may be made within the scope of 30 the inventive idea as implied and claimed.

What I claim as my invention is:

1. A pipe-cleaner comprising a shank having a handle on one end and having its other end formed with a cutting edge and 35 with a helical groove extending inward from said cutting edge, the shank also being formed with a slot which intersects its periphery at the inner end of said helical groove and extends thence inward toward 40 said handle and toward the axis around which the shank is rotatable to actuate the cutting edge, said helical groove being effective to receive cuttings from said cutting edge and also to coat with said slot to hold 45 a wiping strip, substantially as described, for the purpose specified.

2. The structure defined by claim 1 in combination with a wiping strip which tapers from end to end and is attachable to 50 said shank by inserting either end in said slot for either forming a helical coil for cleaning the interior of pipe stems, or forming a mop-like covering over the helical groove and cutting edge.

In testimony whereof I affix my signature.

HOWARD M. MURPHY.
